United States Patent Office.

ISAIAH HERRICK, OF MERRIMACK, NEW HAMPSHIRE.

Letters Patent No. 76,918, dated April 21, 1868.

IMPROVED MODE OF CHURNING BUTTER.

The Schedule referred to in these Letters Patent and making part of the same.

TO ALL WHOM IT MAY CONCERN:

Be it known that I, ISAIAH HERRICK, of Merrimack, in the county of Hillsborough, State of New Hampshire, have invented a new and improved Mode of Churning Butter; and I do hereby declare that the following is a full and exact description thereof, reference being had to the accompanying drawings, and to the letters of reference marked thereon.

Figure 1 is a general view of the churn, with a portion of the front and one end broken out, in order to show the internal arrangement of the parts.

Figure 2 is a plan view of bottom of the churn, showing space over which the floats E E' revolve, and steps for shafts D D'.

A is an iron shaft, provided with a crank, V, and two bevelled gears, B B', which run into two bevelled pinions, C C', (only being shown in drawings,) which are fastened to the two upright shafts D D', which run in suitable boxes or journals fitted into the cover or the churn I and the steps F F'. The shaft A runs in the boxes G G', which are properly fitted to the standard H H'. Upon the shaft D D' are fitted the floats E E', which are held in place and caused to revolve by means of the brass springs O O', which pass through the lower cross-pieces of floats, and into a hole in the shaft D. There is a small hole in the pinions C C', for the purpose of receiving the end of the brass spring P P', thereby holding them from revolving when placing on the floats, when necessary to do so.

The churn is operated by turning the crank b, which, by means of gears B' B' and pinion C C', causes the floats E E' to revolve with great velocity. Further description, if needed, in the caveat, filed April, 1867.

What I claim as my invention, and desire to secure by Letters Patent, is—

The dashers E E', constructed as described, in combination with springs O O', steps F F', cog-wheels B B', pinion C, standards H H', journal-box G, shaft A, and crank V, arranged substantially as and for the purpose set forth.
